UNITED STATES PATENT OFFICE.

LESLIE R. HIGHT AND BERTHA G. HIGHT, OF NEODESHA, KANSAS.

SAD-IRON HANDLE.

1,298,210.

Specification of Letters Patent. Patented Mar. 25, 1919.

Application filed December 6, 1917. Serial No. 205,831.

To all whom it may concern:

Be it known that we, LESLIE R. HIGHT and BERTHA G. HIGHT, citizens of the United States, residing at Neodesha, in the county of Wilson and State of Kansas, have invented certain new and useful Improvements in Sad-Iron Handles, of which the following is a specification.

Our invention relates to new and useful improvements in sad iron handles, and more particularly to the type which are detachable from the main body of the iron, in order that the handle may be removed from the body of the iron, while the iron is being heated, to facilitate a cool temperature of the detachable handle at all times.

Another object of our invention is to provide a device including means carrying the latch lug, whereby the said lug may be guided to and from its locked position.

A further object of our invention is to provide a device having the various parts thereof so constructed and attached to one another, that they may be readily removed, to facilitate the repairing of any part thereof.

A still further object of our invention is to provide reinforcing means between the handle portion and the base, in order that the two parts may be securely bound together, and may be detached from one another if so desired.

Other objects and advantages will be apparent during the course of the following description.

In the accompanying drawings forming a part of the description, and wherein like numerals are employed to designate like parts throughout the same,

Figure 1 is a side elevation of the handle connected to an iron, parts thereof being broken away to show the guide means of the latch lug.

Fig. 2 is a bottom view of the handle, and

Fig. 3 is an end view of the same.

In the drawing wherein for the purpose of illustration is shown a preferred embodiment of our invention, the numeral 1 designates the usual body of a sad iron, adapted for use in connection with a detachable handle. The top of this body 1 is provided with the usual curved recess, and the trans-

verse bar 2, for the reception and locking engagement of the lugs carried by the handle.

Our improved grip consists of a handle portion 3 which is mounted between the two side supports 4. It will be noted that one of the side supports 4 is longer than the other, for a purpose which will hereinafter appear. A substantially flat base 5 is adapted to be secured to the lower ends of the side supports 4 and is provided with a bifurcated end 6, as more clearly shown in Fig. 2 for the reception of this lower end of the side support 4. A pin 7 is passed through the bifurcated ends of the base and the side support 4, to provide a secure connection between the handle and the base.

The opposite end of the base 5 is provided with a similar bifurcated end, said bifurcation being reduced in width and extending through the base to the point substantially intermediate the ends of the base. A block 8 having a longitudinal opening therethrough is adapted to be received in the enlarged portion of the bifurcation and is provided with substantially vertical recesses 9 which are adapted to be arranged adjacent the sides of the bifurcated end. Clamping links 10 are secured to opposite sides of the supporting end 4 and are adapted to have their opposite ends extend into the vertical recesses 9. Screws or any other suitable fastening means 11 are passed transversely through the bifurcated ends of the base, the clamping links 10, then into the block 8, for securing said block and supporting end 4 to the base. The lower end of the other side support 4 is secured on top of the block 8 by means of the link 10, which prevents the turning of the support 4 with relation to the base.

By the provision of this block 8, a slot 12 is formed from the bifurcation, which extends to a point intermediate the ends of the base. An opening 13 is provided in the innermost wall of the base and is adapted to align with the slot 12, for the reception of the inner end of a latch rod 14, said latch rod having its opposite reduced end 15 passing through the opening in the block 8, and projecting beyond the same. A knob 16 is secured to this projected end of the latch

rod, and is preferably made of wood in order that the operator may grasp the same to release the handle from the arm. A latch lug 17 is secured to the latch rod 14, a suitable distance from the inner end thereof, and is adapted to operate within the slot 12 and to abut with the inner wall of the slot 12 when the lug has assumed a locked position. A coil spring 18 is adapted to surround the latch rod and have one of its ends abut with the latch lug 17, and the opposite end thereof abut with the inner side of the block 8. This spring normally urges the latch lug into engagement with the innermost wall of the slot 12. A stationary lug 19 is formed upon the under side of the base, adjacent the slot 12 and projects downwardly and inwardly toward the said slot. The latch lug 17 also projects downwardly and inwardly toward the stationary lug 19 to form a clamp for engaging the bar 2 of the iron 1.

Assuming that the handle is attached to the usual iron as shown in Fig. 1, and it is desired to remove the same therefrom, the knob 16 is moved outwardly, which slides the latch rod outwardly of the opening 13, and the opening through the block 8, in order to move the latch lug against the tension of the spring 18 and away from its co-acting lug. It will be seen that the stationary lug 19 may be readily disengaged with the cross bar 2 by simply moving the handle in the opposite direction. As soon as the knob 16 is released from the operator's fingers the spring will then force the latch lug into engagement with the end of the stationary lug. By this formation and position of the latch lug upon the latch rod, a suitable distance from the inner end thereof, a guide is formed by assigning this end of the rod to the opening 13 in the base.

The grip 3 and the knob 16 are preferably formed of wood, or any conductive material, while the other parts of the device are constructed from metal.

It is to be understood that the form of our invention herein shown and described is to be taken as a preferred example of the same, and that various changes in the shape, size, and arrangement of parts may be resorted to without departing from the spirit

of the invention or the scope of the subjoined claims.

Having described our invention, we 55 claim:

1. A detachable handle comprising a grip portion, a base having a slot therein and recesses in the opposite ends of said slot, a stationary lug carried by said base, a rod movably mounted in said slot and recesses, a lug carried by said rod, and spring means for normally urging the rod inwardly of the base so that the lug carried by said rod engages the stationary lug. 60

2. A detachable handle comprising a grip portion, a base having a slot therein, a depending lug secured to the bottom of said base, a latch rod adapted to operate in the same plane as the base and within the slot 70 in the base, and a lug secured to said rod and adapted to pass through and depend from said slot, and means for normally urging the rod inwardly of the base so that the lug carried thereby engages the stationary lug. 75

3. A detachable handle comprising a grip portion, a base having a slot therein, a lug carried by the base, a latch rod having a shouldered portion within said slot, a latch lug carried by said rod and normally abutting with one end of said slot and engaging its co-acting lug, and said shouldered portion of the latch rod adapted to abut with the opposite end of the slot when the latch lug is in its open position. 80

4. A detachable handle comprising a grip portion, a base having a bifurcation extending from one end to a point substantially intermediate its ends, a stationary lug carried by the base, a detachable block closing the open end of said bifurcation and having an opening therethrough, a rod passing through said bifurcation and opening in said block, a lug secured to said rod, and means for normally urging said lug into engagement with 90 the stationary lug. 95

In testimony whereof we affix our signatures in presence of two witnesses.
